No. 783,051.

PATENTED FEB. 21, 1905.

C. F. LAFRANCE.
SHUTTLE CHECK MOTION FOR LOOMS.
APPLICATION FILED MAR. 23, 1904.

UNITED STATES PATENT OFFICE.

CHARLES F. LAFRANCE, OF TAUNTON, MASSACHUSETTS.

SHUTTLE CHECK-MOTION FOR LOOMS.

SPECIFICATION forming part of Letters Patent No. 783,051, dated February 21, 1905.

Application filed March 23, 1904. Serial No. 199,516.

To all whom it may concern:

Be it known that I, CHARLES F. LAFRANCE, a citizen of the United States, residing at Taunton, in the county of Bristol and State of Massachusetts, have invented certain new and useful Improvements in Shuttle Check-Motions for Looms, of which the following is a specification.

This invention relates to certain new and useful improvements in shuttle check-motions for looms, and has in view the provision of a simple and practical form of checking device which may be readily attached to the lay of any of the ordinary types of looms and presenting simple and effective means for checking the movement of a shuttle as it enters a shuttle-box and preventing rebound thereof, while at the same time not interfering with the action of the picker in throwing the shuttle out of the box.

To this end the invention contemplates a checking-device attachment for the shuttle-box end of looms operating in connection with the usual binder and picker-stick and so arranged as to reduce to a minimum all wear on the picker-stick, while at the same time directly actuated thereby when a shuttle moves into a box.

A special object of the invention is to so arrange the parts of the device in connection with the binder and picker-stick, as to exert a gradually-increasing binding or checking pressure upon the shuttle after the same comes into contact with the picker, thereby checking the motion of the shuttle in such a manner as to positively prevent rebound thereof, and also prevents the filling from breaking. By reason of the checking motion provided for through the medium of the improved device the shuttle can be run very loose in the box and requires less power to throw the same across the lay.

With these and many other objects in view, which will readily appear to those familiar with the art as the nature of the invention is better understood, the same consists in the novel construction, combination, and arrangement of parts, which will be hereinafter more fully described, illustrated, and claimed.

The essential feature of the invention, in-

volved in the structural features of the attachment *per se*, and the relation of its elements to the binder and the picker-stick are susceptible to some change without departing from the scope of the invention; but a preferred embodiment thereof is shown in the accompanying drawings, in which—

Figure 1 is a top plan view of one end of the lay of the loom, showing the improved checking-device attachment associated therewith. Fig. 2 is a side elevation from that side of the lay upon which the attachment is mounted. Fig. 3 is a detail bottom-plan view illustrating the attachment of the centering-plate for the picker-stick. Fig. 4 is a perspective view of the complete checking device.

Like numerals designate corresponding parts in the several figures of the drawings.

In carrying out the present invention no change is required in the ordinary parts of the loom, so for illustrative purposes there is shown in the drawings one end portion of the lay 1 of a loom, which lay is provided with the usual longitudinal picker-stick slot 75 2, accommodating the upper active end portion of the swinging picker-stick 3. The slotted end of the lay also supports the parts of the shuttle-box, including the stationary shuttle-box wall 4 and the opposite movable binder-plate 5, usually having a pivotal support, as at 6, and adapted to be moved with binding pressure against the shuttle as it enters the box.

The checking device constituting the present invention is associated directly with the binder 5 and the picker-stick 3, said checking device including in its general organization a short vertical rock-shaft 7, carrying at its upper end a horizontally-disposed presser-arm 8 and at its lower end a similarly-disposed impact-blade 9. The vertical rock-shaft 7 is journaled in the upper and lower spaced bearing-lugs 10 and 11, formed integrally with and offset from an attaching-plate or bracket 12, 95 which is fastened rigidly to one side of the lay 1 through the medium of screws or equivalent fasteners 13. The horizontally-disposed presser-arm is preferably formed integrally with the upper end of the rock-shaft 7, though 100

any rigid connection will suffice, and at the end united with the shaft the said presser-arm or adjacent portion of the shaft is provided with a short offstanding stop-lug 14, adapted 5 to move against an abutment-shoulder 15, provided at the upper end of the attachment-plate or bracket carrying the lugs 10 and 11. This construction serves to limit the movement of the rock-shaft in the direction of returning 10 the parts to their normal positions under the influence of the retracting-spring 16. This retracting-spring 16 is coiled upon the shaft 7 between the bearing-lugs 10 and 11 and is suitably engaged at one end with the presser-arm, 15 as at 17, whereby the tension thereof may be exerted in a direction for holding the impact-blade 9 beneath the lay 1 and in the path of the picker-stick 3.

The presser-arm 8 is preferably provided 20 at its swinging end with a flattened contact-foot 18, bearing against the outer side of the binder 5, contiguous to one end thereof, and the said arm as well as the impact-blade 9 are preferably both disposed in horizontal 25 planes and maintain a substantial parallelism respectively to the upper and lower sides of the lay. The impact-blade 9 essentially consists of a flat plate presenting a widened and smooth contact-surface for the picker-stick 3 30 to bear against, and in order to provide for proper adjustments said blade preferably has an adjustable connection with the bracket-arm 19, offset from a supporting-collar 20, mounted on the lower extremity of the rock-shaft 35 7 and held in the proper position thereon through the medium of a set-screw or equivalent fastening 21. To provide for the adjustable connection with the bracket-arm 19, the blade 9 is longitudinally slotted at one end, as 40 at 22, to receive the bolt 23, which passes through the arm 19. With the parts in their normal positions the impact-blade 9 lies obliquely beneath the lay in the path of the picker-stick 3, so that immediately upon said 45 picker-stick being engaged by the shuttle entering the box the same moves against the blade 9 and communicates an inward movement to the presser-arm 8, with the result of pressing the binder against the shuttle. As 50 the picker-stick moves forward to throw the shuttle out of the box the pressure thereon is relieved by the parts automatically resuming their normal positions under the influence of the retracting-spring 16. To provide for 55 holding the picker-stick to a centered position within the lay-slot when the impact-blade is bearing against the same, there is employed a centering-plate 24, arranged at one side of the picker-slot and pendent from an adjustable base or base-plate 25, arranged beneath 60 the lay and having a pivotal mounting at one end thereof, as at 26. At its opposite end the base or base-plate 25 has a screw- and -slot mounting 27, whereby the plate 24 may be

adjusted laterally to provide for correctly 65 centering the picker-stick.

From the foregoing it is thought that the construction, action, and many advantages of the herein-described checking device will be readily apparent without further description, 70 and it will be seen that various changes in the form, proportion, and minor details of construction may be resorted to without departing from the spirit of the invention or sacrificing any of the advantages thereof. 75

Having thus described the invention, what is claimed, and desired to be secured by Letters Patent, is—

1. In a shuttle-check, the combination with the lay, the binder, and the picker-stick, of a vertical rock-shaft journaled at one side of the lay, a horizontally-disposed presser-arm rigid with the upper end of the rock-shaft and having a contact-foot at one end engaging with the binder, an impact-blade having an adjustable connection with the lower end of the rock-shaft and normally arranged beneath the lay at an angle to the path of the picker-stick, and a spring coiled on the shaft and arranged to provide for normally turning the shaft in one 90 direction. 80

2. In a shuttle-check, the combination with the lay, the binder, and the picker-stick, of a bracket or plate fitted to one side of the lay and having offstanding bearings and an abutment-shoulder, a vertical rock-shaft journaled in said bearings and carrying a stop-lug co-operating with said shoulder, a horizontally-disposed presser-arm rigid with the upper end of the rock-shaft and having a contact-foot 100 at one end engaging with the binder, a supporting-collar fitted to the lower end of the rock-shaft, an impact-blade having an adjustable connection at one end with said collar and normally arranged beneath the lay at an angle 105 to the path of the picker-stick, and a spring coiled on the shaft and engaged with the part carried thereby to provide for normally turning the shaft under pressure in one direction. 110

3. In a shuttle-check, the combination with the lay, the binder, and the picker-stick, of a spring-returned rock-shaft journaled in an upright position at one end of the lay and carrying at its upper end a presser-arm engaged with the binder, and at its lower end an impact-blade extending beneath the lay across the path of the picker-stick, and an adjustable centering-plate arranged upon the lay at one side of the picker-stick for centering the same, said plate having a pivotal support at one end 115 and a swinging adjustable mounting for its opposite end. 120

In testimony whereof I affix my signature in presence of two witnesses.

CHARLES F. LAFRANCE.
